UNITED STATES PATENT OFFICE.

FREDERIC W. ROBINSON AND KENNETH V. KNAPP, OF NEWARK, NEW JERSEY, AS-SIGNORS TO HANOVIA CHEMICAL AND MFG. CO., OF NEWARK, NEW JERSEY, A CORPORATION OF NEW JERSEY.

ADJUSTABLE LAMP STAND.

Application filed September 15, 1923. Serial No. 662,806.

To all whom it may concern:

Be it known that we, FREDERIC W. ROBINSON and KENNETH V. KNAPP, both citizens of the United States, and residents of Newark, in the county of Essex and State of New Jersey, have invented certain new and useful Improvements in Adjustable Lamp Stands, of which the following is a specification.

This invention relates to improvements in stands and particularly to types adapted to adjustably support electric lamps, as used for scientific and medical purposes.

One of the objects of the invention is to provide a stand composed of an upright post carrying a rotatable and vertically adjustable sleeve provided with clamping means and having an angularly adjustable bracket in which operates a transverse slide carrying the lamp head support.

Another purpose is to produce a device for positively actuating the slide into desired adjustment and locking the same when such adjustment has been attained, means also being provided for rigidly clamping the bracket in any angular adjustment relative to the post.

A further aim is in the provision of an inclinable lamp support having efficient clamping means to retain its angular adjustment and provided with a cradle or socket having inreaching, spring actuated clamps for automatically engaging the lamp used in connection therewith.

Supplementary to the foregoing objects are the provision of means for counterbalancing the weight of the lamp, said means being either engageable to the lamp direct or the bracket at the sleeve as preferred, and associated with the counterweight are means to prevent entanglement of the flexible connecting element used, irrespective of the position of parts.

Still further objects are to provide an apparatus that can be used either for right or left hand operations, in which adjustments can be made by the use of one hand only, and further, to produce a device that can be cheaply and economically manufactured.

These and other objects, unspecified but

apparent further on, are accomplished as hereafter described and shown in the accompanying drawings, forming a material part of this disclosure, and in which:—

Figure 1 is a front elevational view, showing an embodiment of the invention as completely assembled for operating.

Figure 2 is a side view of the same showing the parts in mid position.

Figure 3 is a fragmentary perspective view of the sleeve carried, arm support bracket and adjustable clamp devices used therewith, drawn to an enlarged scale.

Figure 4 is a longitudinal sectional view taken through the center of the same, in the plane of the bracket clamp axis.

Figure 5 is a similar sectional view of the sleeve taken in a plane at a right angle to Figure 4.

Figure 6 is a fragmentary longitudinal sectional view taken through the upper part of the tubular post.

Figure 7 is a sectional view of the lamp head support, showing its automatic and manually adjustable clamp features.

Figure 8 is a side elevational view of the same, showing the support bar connection.

As shown in the drawings the apparatus is composed of a base, its hub 15 having legs 16, preferably three in number, equally spaced and provided at their extremities with castors 17 facilitating its movement over level surfaces.

Rigidly fixed upright in the hub 15 is a tubular post 18 extending to any desired height and surmounted at its top by a throttled cap 19, its upper, outer surface 20 presenting a parabolic curve blending into the central conical cavity 21, enlarged as at 22 and in open communication with the interior of the post.

A cord or like flexible element 23 passes freely through the opening in the cap, its inner end being secured to a counterweight 24 movable within the post and its outer end having a clip 25 engageable with parts to be wholly or partially supported as hereafter described.

It is to be noted that the bight of the cord in passing over the parabolically curved surface 20 is supported with very little fri-

tion and it is found by experience that the cord cannot become entangled, fouled or in any way rendered unable to perform its function under the most severe tests when such device is used.

Engaged on the post 18 is a freely fitting sleeve 26 having an annular chamber 27 in which operate a pair of opposed flat springs 28 held by rivets 29, the free upper ends of the springs being engageable by a hand operated screw 30, interchangeable in either of the bosses 31, formed on the sleeve near its upper end, registering with the springs, which can thus be clamped forcibly against the post, holding the sleeve securely in adjustment.

The two springs and bosses are used so that the screw may be changed from right to left hand as preferred or more convenient; due to the interposition of the springs the post is not marred or disfigured, even if the screw be forced tightly inward, the function of the springs being mainly that of a gib or cushioning element.

Extending laterally outward from the collar 26, at a point near its lower end and at a right angle to the bosses 31, is a larger diametered boss 32 having a flat level surface 33 from which projects an integral stud 34, its end 35 being squared to receive a washer-like plate 36 having a similarly shaped opening.

The stud is drilled and tapped to receive a knurled head clamp screw 37 adapted to press the plate 36 forcibly towards the surface 33, the plate impinging against a lug 38, forming part of a bracket 39, and bored to fit the stud 34 on which it is revolvably mounted.

Intermediate the inner face of the lug 38 and outer face 33 of the sleeve boss, is interposed a series of friction plates arranged in grouped alternating order, one group 40 being constrained to the boss 32 by a pin 41, and the other group 42 being held by a similar pin 43 to the lug 38.

Thus when the screw 37 is slackened, the bracket 39 may be rotated on the stud 34 nearly a full turn, or until the pins 41 and 43 interfere, it being understood that both pins pass freely through peripheral projections on the plates 40 and 42 as shown; on the contrary when the clamp screw is set up, the several alternatingly arranged friction plates are pressed into forcible contact, holding the bracket 39 rigidly to the sleeve.

The bracket 39 extends in opposite directions past the base of the boss 32 and contains a longitudinal recess suited to guide and support a rectangular tube 44, which, together with a toothed rack 45, rigidly secured to the tube, is freely slidable therein.

Meshing with the teeth of the rack 45 is a spur pinion 46 mounted between lugs 47 and 48 extending from the bracket 39, opposite

the boss 32, the pinion being slidably engaged on a polygonal spindle 49 rotatable in the lugs and having a stem 50 extending through the lug 48, this stem being fixed in a knob 51, below and in register with the head of the screw 37.

A round boss on the face of the lug 48 contains a concentric row of holes 52 and fixed in the inner face of the knob 51 is a single pin 53 engageable in any of the holes 52.

To operate the rack the knob 51 is drawn outwardly to clear the pin 53, the spindle sliding through the pinion and lug 47 until its limit of movement has been reached at the bottom of the recess 48' in the lug 48, whereupon rotating the knob 51, the pinion will be turned, transmitting longitudinal motion to the tube and rack, which, as will later be seen, constitute a support bar.

When this bar has been moved in the bracket to secure the desired adjustment, the knob is pressed inwardly and the pin 53 engaged in the closest adjacent hole, locking the bar from further longitudinal movement.

It is obvious that the cross section of the spindle 49 may be as shown or otherwise, its function being to transmit rotary motion to the pinion and permit necessary longitudinal movement in locking or unlocking the knob 51 without disengaging the pinion.

In order to prevent excessive movement of the elements 44 and 45, a stop plug 54 is inserted and fastened in one end of the tube 44, this plug making contact with the end of the bracket, but obviously another form of limit stop may be substituted.

At the opposite or front end of the bar is rigidly fastened an arm 55 acting as a stop and extending in alignment with the tube and terminating in forks 56, thru which passes a rod 57 having a threaded end engaging a nut 58, held from rotation by a pin 59; the other end of the rod is integral with or rigid in a knurled clamp head 60, by rotation of which the forks may be forced towards each other.

Entering between the forks is a tenon 61, rotatable on the rod 57 and having a plurality of transversely drilled holes in which are entered rods 62 of any preferred frictional material, as fiber, extending slightly outward so as to make direct contact with the inner faces of the forks and by which the tenon may be clamped.

This tenon extends from a clutch head 63, the central flat portion 64 of which is in register with the tenon and gradually increased in width, its upper edge having a flat bead 65.

The lower part of the head contains opposed lateral recesses 66 curved and suited to receive semi-cylindrical rockers 67, formed on the lower ends of clamps 68, the concave

upper members 69 extending above the flat bead 65, forming a socket adapted to engage a lamp body, holding the same securely but removably on the stud.

5 These clamps are each independently pressed toward the head element 64 by coiled compression springs 70 fitting in recesses 71 in the outer sides of the elements 68, the outer ends of the springs abutting respectively the head 72 and nut 73 of a bolt 74, passing through the head element 64 and normally holding the clamps tightly thereagainst.

15 This structure is best shown in Figures 7 and 8 and it will be seen that the lamp, generally designated by the numeral 100, has a body element 101 of substantially ovoidal cross section that may be easily removed from the socket by a combined 20 twisting or rotary and raising movement, one or both of the clamps moving on their rockers 67.

25 The purpose of this clamp socket is to hold the lamp head firmly and provide means whereby the same can be tilted at any preferred inclination by the knob 60.

30 Such lamps are usually cooled by water circulation and for this purpose have attached to them flexible pipes 76 and 77, respectively inlet and outlet, connecting with a supply source and discharge.

35 A cable 78 for supplying current to the lamp is arranged substantially parallel to the tubes and over them, these three elements normally extending rearwardly over the curved upper surface of the lug 38 and are prevented from falling off by a guard 79 formed at the upper portion of the plate 36, said plate being reduced in width and provided with an outturned extension 80.

40 The clip 25, carried at the free end of the counterbalancing cord, is engageable with the extension 80, or it may be engaged with the handle element 102 of the lamp head 45 as shown in Figures 1 and 2.

45 From the foregoing it will be clear that the lamp head 100 may be easily engaged in the socket in a firm and secure manner or removed therefrom at will, and when disengaged its weight is taken by the counterbalancing device direct.

50 It is further apparent that the lamp head socket can be inclined on the axis 57 and firmly clamped when the desired adjustment is obtained.

55 In addition the lamp head may be extended or retracted by manipulating the knob 51 and also locked thereby in a positive manner.

60 The lamp support bar 44 may be held at any desired angle or turned nearly vertical and rigidly clamped in such adjustment, while the sleeve 26 can be rotated on the post, raised or lowered and also rigidly clamped in any desired position, these sev-

eral devices rendering the lamp universally adjustable and applicable in practice in directing the rays as may be desired.

Although we have described our improvements with considerable detail and with respect to certain particular forms of our invention, we do not desire to be limited to such details since many changes and modifications may well be made without departing from the spirit and scope of our invention in its broadest aspect.

Having thus described our invention, what we claim as new and desire to secure by Letters Patent, is:—

1. A therapeutical lamp stand comprising 80 a castored base, an upright fixed therein, a sleeve slideable on said upright, said sleeve having an annular chamber, spring grip strips fixed in opposite sides of the chamber, means for pressing either of said strips into 85 forcible clamping engagement with said upright, lamp supporting means adjustably carried on said sleeve, an electric cable connecting with said lamp, and resilient means carried on said sleeve for supporting and guiding said cable.

2. A therapeutical lamp stand comprising 95 a castored base, an upright fixed therein, a sleeve slideable on said upright, means for clamping said sleeve to said upright at any point along the entire length thereof, a bracket pivoted on one side of said sleeve to extend outwardly therefrom, means for clamping said bracket in angular adjustment 100 relative to the axis of said sleeve, a rigid tubular lamp supporting arm of rectangular cross section movable lengthwise in said bracket, means to adjust said arm lengthwise in the bracket, and means for positively locking said arm, said locking means being 105 combined with the adjusting means.

3. A therapeutical lamp stand comprising 110 a castored base, a straight tubular upright fixed therein, a sleeve slideable on said upright from end to end thereof, means for adjustably securing said sleeve on said upright, said sleeve having a laterally extending stud, a bracket pivotally mounted on said stud, a plurality of friction washer plates on said stud interposed between said 115 sleeve and bracket, said plates being secured in alternate relation respectively to the sleeve and bracket, hand operated means for clamping said plates to prevent relative rotation of the alternate plates and to hold 120 said bracket in adjustment, and a hollow rectangular lamp carrying arm movably supported in said bracket.

4. A therapeutical lamp stand comprising 125 a movable base, a hollow upright fixed therein, a sleeve adjustable lengthwise on said upright, an arm adjustable lengthwise in said sleeve, a lamp at one end of said arm, a weight freely movable in said upright, a 130 flexible cord connecting said weight with

- 5 said lamp, and a hollow cap on said upright through which said cord passes, said cap having a parabolically curved, conical outer surface over which the cord freely moves 55 5 in any direction to accommodate said arm and lamp.
5. A therapeutical lamp stand comprising a movable base, a hollow upright fixed therein, a sleeve slideable and rotatable on the upright, a flexible gib in said sleeve, means for clamping said gib against said upright to prevent motion of the sleeve, a bracket adjustably rotatable on the side of said sleeve, a rack bar in said bracket, means 60 10 for actuating said bar, means for positively locking said bar, stops on the ends of said bar, and a clamp head carried at one end of said bar.
6. A therapeutical lamp stand comprising a movable base, a hollow upright fixed therein, a sleeve slideable and rotatable on the upright, a flexible gib in said sleeve, means 65 15 for clamping said gib against said upright to prevent motion of the sleeve, a bracket adjustably rotatable on the side of said sleeve, a rack bar in said bracket, means for actuating said bar, means for positively locking said bar, a stop at one end of said bar, a fork at the other end, and a lamp 70 20 carrying socket pivoted in said fork.
7. A therapeutical lamp stand comprising a base, a post fixed therein, a bracket adjustable on said post, said bracket being inclinable, a rack bar in said bracket, a pinion 75 25 engaging said bar, a knob for rotating said pinion, means controlled by said knob for locking the pinion, a lamp head carried at one end of said bar, and means for inclining said head relative to said bar.
8. A therapeutical lamp stand comprising a base, a post fixed therein, a bracket adjustable on said post, a bar slideable in said bracket, means for actuating said bar, a fork at one end of the bar, a lamp head 80 30 socket, a tenon on said socket pivoted in said fork, frictional elements in said tenon, and means for clamping the fork on said friction elements to prevent movement of said socket.
9. A therapeutical lamp stand comprising a base, a post fixed vertically therein, a 85 35 sleeve adjustable on said post, a bracket pivoted on said sleeve at the side thereof, a bar slideable in the bracket, means for actuating and controlling the movement of said bar, a lamp head socket inclinably engaged on one end of said bar, opposed spring actuated means associated with said socket adapted to automatically engage and clamp the lamp head, said means maintaining the 90 40 head in an upright position.
10. The combination with a lamp having a body element of substantial ovoidal cross section, of a snap socket receptive of said lamp element, said socket having a fixed central web beaded on its upper surface to act as a seat for said lamp element, a pair of opposed clamps rockingly engaged on said web at their lower ends, their upper ends being suited to receive said body element above the bead, and a spring in each clamp urging its upper end inwardly. 70 45
11. A lamp stand comprising a base, a hollow standard, a lamp head, means slideable and rotatable on said standard to adjustably support the lamp head, a counter-weight for said lamp, said counter-weight being freely contained in said standard, a flexible connection between said lamp head and said counter-weight, and a hollow cap 50 55 fixed on said standard through which said connection passes, said cap having a parabolically curved surface against which the connection makes contact.
12. A lamp stand having a standard, an arm adjustably connected thereon, a lamp head having rear extensions, one of said extensions acting as a handle by which the head can be maneuvered, the other extension being of elliptical cross section, its longer axis being in a horizontal plane, and a pair of opposed clamps on one end of said arm, said clamps being automatically engageable with the second named extension 95 60 upon the application of moderate pressure. 90

This specification signed and witnessed this 6th day of September, 1923.
